N. McL. CAMPBELL,
SEA ANCHOR,
APPLICATION FILED NOV. 22, 1917.

Patented Nov. 19, 1918.

UNITED STATES PATENT OFFICE.

NORMAN McIVOR CAMPBELL, OF CHISWICK, LONDON, ENGLAND.

SEA-ANCHOR.

1,285,558.

Specification of Letters Patent. Patented Nov. 19, 1918.

Application filed November 22, 1917. Serial No. 203,398.

To all whom it may concern:

Be it known that I, NORMAN McIVOR CAMPBELL, a subject of the King of Great Britain, and resident of Number 20 Homefield Road, Chiswick, in the county of London, in the Kingdom of England, have invented new and useful Improvements in Sea-Anchors, of which the following is the specification.

10 The invention relates to improvements in sea anchors as described in the present specification and illustrated in the accompanying drawings that form part of the same.

15 The invention consists essentially in the novel construction and arrangement of a float and a blade, whereby a definite resistance to the drift of the boat is set up, and the violence of a sea is to some extent mitigated.

20 The objects of the invention are to save the lives of the passengers and the crews in disasters to ships sailing the waters, to steady all types of boats in rough weather, particularly the smaller boats serving as tenders or life saving craft to the comparatively large steamers or steamships, to reduce the cost of maintenance of such equipment, to conserve space in life boats and 30 generally to provide a simple, durable and efficient sea anchor.

In the drawings, Figure 1 is a front elevation of the anchor.

Fig. 2 is a side elevation.

35 Like numerals of reference indicate corresponding parts in each figure.

Referring to the drawings, the float 1 is here shown in cylindrical shape and made of a tubular metal center 2 fitting into and 40 rigid with the end caps 3, the latter having the lugs 4 projecting downwardly therefrom.

45 It is of course obvious that the float 1 is water tight and also that it may be made of any material and in many different shapes, so long as it comes within the scope of the novel matter claimed within.

The eye 5 is screw threaded centrally into the part 2, and forms the support for the 50 hook of the block and tackle 6, the purpose of which is explained in detail hereinafter.

The arms 7 are secured to the lugs 4 by the eye bolts 8 and nuts 9 preferably on the rear side of said lugs 4.

55 The said arms 7 are adapted to fold closely to said float 1 in the collapsed state

of the anchor and in their extended positions stand out at right angles therefrom.

Furthermore it may be said that the arms 7 are in round rod form extending from the 60 flat heads 8 secured to said lugs to the flat sections 9 having bolt holes therethrough.

The blades 10, in upper and lower sections 11 and 12 secured together by the hinges 13, are rigidly held to the arms 7 by the 65 plain bolts 14 and nuts 15, and the eye bolts 16 and nuts 17.

The flat sections 9^a of said arms engage the rear sides of the sections 11 and 12; consequently the blades in their extended 70 position present a considerable surface to the water below the float 1, the shape being preferably rectangular.

The rigidity of the structure, especially the hinged blades in relation to the float is 75 a very strong feature of this invention, but on the other hand the collapsibility is of great importance and by reference to the drawings in following this description, it will be seen that by the removal of a few 80 bolts or other fasteners, the parts can be separated and stowed away within a very small space.

The bridle is formed of the looped ropes 18 and 19 the rope 18 at its ends being secured to an eye bolt 8 and an eye bolt 16 on the one side and the rope 19 being secured to an eye bolt 8 and an eye bolt 16 on the other side, said ropes centrally passing through and engaging the shackle 20. 90

The hawser 21 is also secured to the shackle and extends to the boat; therefore the strain of the pull will always maintain the anchor in a vertical as well as a transverse position in relation to said boat, that 95 is to say, across the bow of the boat though of course a reasonable distance therefrom.

The block and tackle is intended to carry an oil receptacle for smoothing the sea in front of the boat and thus lessen the risk 100 of seas breaking over the bow and flooding or upsetting the boat.

In the operation of this invention, the parts collapsed and separated are stowed away conveniently in the life boat in such 105 a way as to be ready for instant assembling and use.

The parts are assembled by opening out the arms 7 to their extended position and unfolding the blades to their open position. 110

The flat sections of said arms are placed across the blades close to the ends thereof

and rigidly secured thereto by the plain bolts 14 and eye bolts 16.

The bridle is already attached to the bolts; therefore as soon as the hawser is 5 suitably secured to the shackle and in the boat, the device is ready for launching.

The anchor floats out to the extent of the 10 length of the hawser paid out and immediately assumes its vertical position, the said blades being suspended below the float 1 and maintaining their position edge downward.

It will thus be seen that the full face of 15 the blades offers resistance to the pull of the hawser and this keeps the stem of the boat up to the sea, thereby preventing any chance of the boat taking said sea broad-side on.

The float on top of the water serves to 20 break the crests of the waves which materially lessens the chances of swamping.

There are many other practical advantages for this invention, as for instance the 25 facilities it offers for pouring oil on the turbulent waters in the right place in front of the boat not at the sides, also the durability and efficiency, for many others do not maintain their buoyancy and instead of being a protecting drag, they become a dangerous drag; furthermore canvas and many 30 other forms of drags or sea anchors are very destructible and frequently are rendered useless by mold, dampness, rats and other causes; therefore the present invention which can be made to suit any climate 35 or conditions is of general service through-

out the world. Various changes may be made without departing from the spirit of the invention so long as they remain within the scope of the claims for novelty following.

What I claim is:—

1. A sea anchor comprising a float, collars rigidly secured to said float and having lugs projecting therefrom, a barrier member formed in longitudinal sections hinged together, arms pivotally secured to said lugs and adapted to fold up to said float in the collapsed state of the anchor and in their extended position stiffening 45 said barrier sections, both securing said arms to said barrier member and readily removable and a bridle secured to the lugs of said collars and to the lowermost fastening bolts.

2. A sea anchor comprising a float, arms extending downwardly from said float, a barrier in vertical blade form, secured to said arms, a bridle adapted to make a substantially even pull on said float and blade 60 portion and fastened to a hawser and a traveling cable connection from said float, adapted to be fastened to the boat and form a carrier from said boat to and from said float.

Signed at Montreal, Canada, this 31st day of October, 1917.

NORMAN McIVOR CAMPBELL.
